DESIGN FOR A CABINET

Edmond J. Spence, Montclair, N. J., assignor to
National Desk Company, Inc., Herkimer, N. Y.,
a corporation of New York

Application August 26, 1946, Serial No. 132,864

Term of patent 7 years

(Cl. D33—19)

To all whom it may concern:

Be it known that I, Edmond J. Spence, a citizen of the United States, residing at Montclair, in the county of Essex and State of New Jersey, have invented a new, original, and ornamental Design for Cabinet, of which the following is a specification, reference being had to the accompanying drawing, forming part thereof.

In the drawing:

Figure 1 is a perspective view of the cabinet in closed position, and

Figure 2 is a perspective view of the cabinet in opened position.

The dominant features of my design are shown in full lines.

I claim:

The ornamental design for a cabinet, as shown and described.

EDMOND J. SPENCE.
